UNITED STATES PATENT OFFICE.

GEORG OERTGE AND CARL SCHMITT, OF WORMS, GERMANY.

TROUSERS PRESS.

Application filed October 1, 1925, Serial No. 59,929, and in Germany September 11, 1924.

This invention relates to a trousers press designed to preserve the creases and to do away with the repeated ironing of the trousers which is bad for the same.

According to the invention a slide is arranged in a pocket made from suitable material, springs, rubber bands or the like being provided for pushing the slide in lateral direction out of the pocket when a locking element has been released, the edge of the pocket as well as the edge of the slide engaging with the crease of the trousers when the apparatus is inserted into the trousers leg.

An embodiment of the invention is shown, by way of example, on the accompanying drawing in which:

Fig. 1 shows in elevation the pocket with the slide inserted.

Fig. 2 is a cross section of Fig. 1.

Fig. 3 shows the apparatus in working position.

In a pocket *a* a slide *b* is located which has a pin *c* engaging with a bayonet slot *d* of the top plate of the pocket *a*. When the slide *b* is in the position of rest pin *c* engages with an upwardly directed notch *f* at the inner end of slot *d*. Rubber bands *g* or springs are attached at the one end to the inner surface of the plates of the pocket and at the other end to the surfaces of slide *b*.

The operation of the apparatus is as follows:

After the apparatus has been inserted into a trousers leg the slide *b* which at the lower end projects from the lower edge of the pocket *a* is pulled down so that pin *c* is pulled out of engagement with notch *f* and enters the slot *d* so that the slide is moved forward by the pull exerted by the rubber bands *g* and the rear edge of the pocket *a* and the front edge of slide *b* are pressed into the opposite creases of the trousers leg.

I claim:

A trousers press comprising in combination a pocket made of suitable material having a bayonet slot in its top plate, a slide made of suitable material movably mounted in the pocket, a pin on said slide engaging with said bayonet slot of the pocket, and rubber bands attached at the one end to said pocket and at the other end to said slide and designed to pull the slide partly out of the pocket when said pin is released from the notch of said bayonet slot so that the edge of said pocket and the edge of said slide are strongly pressed into the opposite creases of the trousers leg.

In testimony whereof we affix our signatures.

CARL SCHMITT.
GEORG OERTGE.
